(57) **CLAIM**

The ornamental design for a cooking stove as shown and described.

DESCRIPTION

1. Cooking stove

1.1 : Front, Right, Top Perspective view

1.2 : Back, Left, Bottom Perspective view

1.3 : Front

1.4 : Back

1.5 : Left

1.6 : Right

1.7 : Top

1.8 : Bottom

FIG. 1 is a front, right, top perspective view of the cooking stove; FIG. 2 is a rear, left, bottom perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; FIG. 8 is a bottom plan view thereof.

The broken line showing is for the purpose of illustrating environmental features and forms no part of the claimed design.

1 Claim, 8 Drawing Sheets
